UNITED STATES PATENT OFFICE.

THOMAS W. WATKINS, OF KANSAS CITY, MISSOURI.

PORTABLE GRINDING AND POLISHING MACHINE.

1,386,820.

Specification of Letters Patent. Patented Aug. 9, 1921.

Application filed April 5, 1920. Serial No. 371,414.

To all whom it may concern:

Be it known that I, THOMAS W. WATKINS, a citizen of the United States, residing at Kansas City, in the county of Jackson and 5 State of Missouri, have invented a certain new and useful Improvement in Portable Grinding and Polishing Machines, of which the following is a specification.

My invention relates to improvements in 10 portable grinding and polishing machines.

One of the objects of my invention is to provide a novel machine adapted for use in polishing floors, walls, tables and similar plane surfaces or for grinding purposes, and 15 which is simple in construction, cheap to manufacture, easy to manipulate, durable, not liable to get out of order, and which is efficient in operation.

My invention provides further novel 20 means by which different abrading or polishing devices may be applied to the machine or removed therefrom.

The novel features of my invention are 25 hereinafter fully described and claimed.

In the accompanying drawing, which 30 illustrates the preferred embodiment of my invention,

Figure 1 is a top view of my improved 35 machine shown partly broken away.

Fig. 2 is a side elevation, partly broken 40 away, of the same.

Fig. 3 is a top view, partly broken away, showing an abrading device and a polishing 45 device mounted on the armature shaft.

Similar reference characters designate 50 similar parts in the different views.

The machine is provided a support comprising, preferably, a horizontal tubular body 1, a tubular arm 2 communicating internally with the body 1, and an arm 3 attached to the body 1 by a transverse bolt 4. The arm 3 is preferably provided with an inclined tubular socket 5 adapted to receive an inclined handle 6.

The arm 3 is provided with a detachable portion 7 attached to the main portion of the arm by removable bolts 8 and provided with a bearing 9 adapted to detachably support a horizontal rotary armature shaft 10 of an 55 electric motor having a body or casing 11 attached to and carried by the tubular arm 2.

For carrying the machine upon a floor, table or other smooth surface, casters 12 may

be respectively attached to the body 1 and arms 2 and 3. 55

Electrical conducting or connecting means comprising a cable or cord 13 containing the usual conducting wires is located in the body 1 and tubular arm 2 and connects the motor with suitable socket connection means 60 14 adapted to detachably receive in the usual manner an ordinary connecting plug 15, which may be connected in the usual manner to a lamp socket.

The armature shaft 10 is adapted to have 65 removably secured to it, intermediate of the body 11 and the bearing 9, a device such as a polishing wheel 16, provided with a set screw 17, adapted to bear on the shaft 10. By removing the bolts 8, the portion 7 may 70 be detached and the bearing 9 slipped off from the shaft 10, thereby permitting the wheel 16 being slipped on or off the shaft 10. The outer end of the shaft 10 is adapted to have removably mounted upon it an adapter 75 18, in which may be mounted an abrading device 19, Fig. 3.

In the operation of my invention, the portion 7, being detached, the polishing wheel 16, or other device to be used, is slipped on the 80 shaft 10 and rigidly attached thereto, after which the portion 7 is fastened by the bolts 8 to the arm 3, with the shaft 10 mounted in the bearing 9. If the current is now turned on, the motor will be operated, thereby revolving the wheel 16 with the armature shaft 10. The wheel 16 is of a diameter such that it will have a slight pressure on the floor or other surface which pressure can be decreased by pressing downwardly upon the 85 upper end of the handle 6, which extends rearwardly beyond the vertical plane of the caster 12, which is mounted on the body 1. Or the pressure may be increased by pressing downwardly on the handle forwardly of 90 the caster just referred to. By moving the machine about on the surface which is being polished, different parts thereof may be polished or ground as the case may be depending upon the nature of the tool mounted 95 on the armature shaft.

The caster 12 which is on the body 1 is capable of longitudinal adjustment thereon. In the operation of the machine, the casters on the arms 2 and 3, if desired, as well as the 100 other caster may be removed.

I do not limit my invention to the structure shown and described, as many modifications, within the scope of the appended claims, may be made without departing 5 from the spirit of my invention.

What I claim is:—

1. In a grinding and polishing machine, a tubular support having two arms, one of which is tubular and interiorly communicating with said support, the other having a shaft bearing, a motor having a body carried by said tubular arm and provided with a horizontal armature shaft mounted in said bearing and adapted to have secured thereto 10 an abrading or polishing device, and electrical conducting means connected with said motor and located in said tubular arm and support.

2. In a grinding and polishing machine, a support having casters adapted to rest on a floor, the support having a tubular body having two arms one of which is tubular and interiorly communicating with the body, the other arm having a detachable 25 portion provided with a shaft bearing, the last named arm having a socket adapted to receive a handle, a motor having a body carried by the tubular arm and provided with a horizontal armature shaft, said shaft bearing portion being arranged to detachably support said shaft, the shaft being arranged to have attached thereto intermediate of said body and said shaft bearing portion a polishing or abrading device, and 30 electrical connecting means connected with said motor and located in said tubular arm and tubular body, substantially as set forth.

3. In a grinding and polishing machine,

a support comprising a tubular body having two arms one of which is tubular and interiorly communicating with said body, said tubular body having means for connection with a socket member, the other arm having a shaft bearing and having a socket 40 adapted to receive a handle, a motor having a body attached to and supported by said tubular arm and having a horizontal armature shaft mounted in said bearing and adapted to have secured to it an abrading or polishing device, and electrical connecting means located in said tubular body and said tubular arm and connecting said motor with said socket member connecting means, 45 substantially as set forth.

4. In a grinding and polishing machine, a support comprising a tubular body having means for connection with a socket member and provided with two arms, one of which is tubular and communicating interiorly with said body, the other arm having a 50 shaft bearing portion and an inclined socket, a handle mounted in said socket, a motor carried by the tubular arm and having an armature shaft arranged for detachable support in said shaft bearing and adapted to have secured thereto intermediate of said bearing portion and the body of the motor a polishing or abrading device, and electrical connecting means located in said tubular body and said tubular arm and connecting 55 the socket connecting means with said motor, substantially as set forth.

In testimony whereof I have signed my name to this specification.

THOMAS W. WATKINS.
